UNITED STATES PATENT OFFICE.

LEONARD KISSNER, OF LANCASTER, OHIO, ASSIGNOR TO THE HOCKING VALLEY MANUFACTURING COMPANY.

MEANS FOR OPERATING FEED-ROLLS.

SPECIFICATION forming part of Letters Patent No. 380,579, dated April 3, 1888.

Application filed October 20, 1887. Serial No. 252,902. (No model.)

To all whom it may concern:

Be it known that I, LEONARD KISSNER, of Lancaster, in the county of Fairfield and State of Ohio, have invented certain new and useful 5 Improvements in Means for Operating the Feed-Rolls for Straw-Cutters; and I do hereby declare the following to be a full, clear, and exact description of the invention, such as will enable others skilled in the art to which it applies to make and use the same.

My invention relates to means for operating feed-rolls for straw-cutters.

Prior to my invention one of a pair of feed-rolls has been journaled in movable bearings, 15 and provided with a universal joint attached to one end of its shaft and to a rocking pinion which was adapted to engage a pinion on the end of the shaft of the stationary roll. With such a construction, when the gear-wheels, 20 move out of a vertical plane, there is an undue wearing and cutting of the cogs when the machine is in motion, thus causing the parts to become impaired in a short time.

It is the object of my present invention to 25 obviate this objection and so construct the device that the driving pinions are always kept in a vertical plane, while one of the feed-rolls is permitted to have a rising-and-falling motion in its bearing at either or both ends of the 30 roll.

With this object in view my invention consists in certain novel features of construction and peculiar combinations and arrangements of parts, as will be hereinafter set forth, and 35 pointed out in the claim.

In the accompanying drawings, Figure 1 is a side elevation of a pair of rolls having my improvements applied thereto. Fig. 2 is a similar view with the adjustable roll in the 40 reverse position. Fig. 3 is a view of the universal joints and connecting-rod detached.

A represents a portion of the frame-work of a straw-cutter having a feed-roller, B, mounted in fixed bearings therein. The shaft B' of this 45 roller is extended horizontally somewhat beyond the frame A and provided at or near its free end with a pinion, a.

Immediately beneath the roller B is another roller, C, mounted in sliding bearings, suitable 50 springs, a', being provided beneath the journals of this roll to yieldingly retain the two

rolls in their normal position, or in contact, and permit the lower roll to yield when a hard unyielding substance passes between them.

It will of course be seen that instead of journaling the movable roll beneath the roll in fixed bearings the reverse arrangement may be adopted with equal advantage, as it is simply a matter of choice which roll shall be above and which below.

In order to drive or rotate the movable roll while the machine is in operation without affecting the relative arrangement of the gearing, I connect the shaft of said movable roll with its driving pinion b by means of two universal joints, D D, and an interposed connecting-rod, E.

The universal joints D D will preferably be made of the usual form, comprising two collars, c c, having ears d, each collar being pivotally connected to a central disk at two points; or these joints D may be of any other desired construction. The head c' of one collar c of each of the universal joints is provided with a preferably square or angular perforation, e, for the reception of the squared or angular end of the connecting-rod E. The connecting-rod E is adapted to have a sliding movement in one or both of the joints D, as one or the other end of its attached roll is elevated or lowered by the passage between them of more material at one end than at the other. The rod E will be provided at its ends with suitable retaining-pins to prevent it from becoming detached from the joints D. Thus 75

it will be seen that when more material passes between the rolls at one end than at the other one roll will be forced away from the other, and at the same time will continue its revolutions and feed more material through the rolls 80 without changing the relative position of the driving mechanism. This is a very important feature in the construction of feed-cutters, and is very effectually accomplished by providing two universal joints between the movable roll 85 and its driving-pinion, and connecting these joints by means of a rod having a sliding connection with the joints, as above explained.

Slight changes might be made in the constructive details of my invention without departing from the spirit thereof or limiting its scope; hence I do not wish to limit myself to

the exact details of construction herein set forth; but,

Having fully described my invention, what I claim as new, and desire to secure by Letters 5 Patent, is—

The combination, with a roller journaled in fixed bearings and having a shaft extending therefrom with a driving gear-wheel thereon, of an adjustable roller journaled in movable 10 bearings and provided with a universal joint, a shaft having a gear-wheel thereon meshed with the driving gear-wheel, said shaft having

a universal joint at one end, and an angular bar adapted to have a sliding connection in the angular openings of said universal joints, 15 substantially as set forth.

In testimony whereof I have signed this specification in the presence of two subscribing witnesses.

LEONARD KISSNER.
